[57] CLAIM

The ornamental design for a disc magazine case, as
shown and described.

DESCRIPTION

FIG. 1 is a perspective view of a disc magazine case
showing my design with the cover in the open position;
FIG. 2 is a perspective view thereof, with the cover in
the closed position as when a disc is inserted;

FIG. 3 is a top plan view of FIG. 2;

FIG. 4 is a bottom plan view thereof;

FIG. 5 is a left side elevational view of FIG. 2;

FIG. 6 is a right side elevational view thereof;

FIG. 7 is a rear elevational view thereof; and,

FIG. 8 is a front elevational view thereof.
